CLAIM

The ornamental design for a pair of linked candles, as
shown and described.

DESCRIPTION

FIG. 1 is a side elevational view of the pair of linked
candles showing my new design, the opposite side being
a mirror image;

FIG. 2 is an end elevational view thereof with the
candles in an alternate position, the opposite end view
being a mirror image;

FIG. 3 is a top plan view thereof; and

FIG. 4 is a bottom plan view thereof.

FIG. 1**FIG. 2**

FIG. 3

FIG. 4
